UNITED STATES PATENT OFFICE.

WILLIAM H. PAIGE, OF SPRINGFIELD, MASSACHUSETTS.

DUMPING-CAR.

SPECIFICATION forming part of Letters Patent No. 233,542, dated October 19, 1880.

Application filed August 16, 1880. (No model.)

To all whom it may concern:

Be it known that I, WILLIAM H. PAIGE, of Springfield, in the county of Hampden and State of Massachusetts, have invented a new 5 and useful Improvement in Dump-Cars, which has not been patented in any foreign country to any person with my knowledge and consent, of which the following is a specification.

The object of my invention is to provide a 10 railway-car from which the whole contents may be easily and quickly dumped from either side by manipulating the mechanism connected therewith, and which is illustrated in the accompanying drawings, in which—

15 Figure I is a side view of a dump-car having my invention applied. Fig. II is a plan view of the frame of the same having the mechanism applied. Fig. III is an end view of the car. Fig. IV is a vertical longitudinal 20 section of the car, showing the shipping lever and rod which operates the side bearing, and the clutches which are connected with the winding-shaft, and showing the side bearing thrown up, with the forward clutch thrown out 25 from the winding-drum. Fig. V is a vertical longitudinal section through the bunter-socket. Fig. VI is a vertical longitudinal section, showing the clutch-operating rod, which also moves the side bearing, and with the latter in its 30 vertical position. Fig. VII is a front view of the buffer-socket, and Fig. VIII is a front view of the braces between which the buffer-socket revolves, and by which it is held in place.

In the drawings, A represents the two side 35 sills of the car, and C C represent two other inside sills or timbers, all extending in a direction lengthwise the car, and to which are secured the cross-timbers and floor-boards of the car, and to the lower side of the car, 40 or beneath the floor, are secured suitable bearings, in which are arranged to revolve easily the shafts 14, one on each side, extending lengthwise the car, on each of which shafts is a drum, 8, arranged to revolve freely on the 45 shaft. Two clutches—one, 6, on one side of the drum, and another, 7, on the other side—are so keyed to the shaft as to revolve only with the shaft, and so as to slide to and fro along the shaft and engage with the drum by 50 teeth or projections on the clutch and also on the sides of the drum, and cause the drum to

revolve, according as one or the other clutch is brought up against the drum.

A rod, 2, is arranged to move longitudinally in suitable bearings near each shaft, upon 55 which rod is a projection, 5, to engage with and move the clutch 6 to and fro along the shaft, and also a projection, 9, to move the other clutch, 7, along the shaft in the same manner, and these clutches are so adjusted 60 with reference to the rod 2 that when one clutch is in engagement with one end of the drum the other clutch is moved away from the other end, say, from six to eight inches, and the rod 2 at the end of the car is connected with 65 a pivoted lever, 1. This rod 2 is also connected, by an arm, 4, with a pin or arm on the side bearing, D, which is a heavy metallic piece suspended from a shaft or pivot, 20, secured to the bottom of the car, one of these 70 bearings on each side of the car at each end, its lower end resting on the truck-beam, and this side bearing, D, is so connected to the rod 2 that when the latter is moved forward to engage the clutch 6 with the end of the drum 75 8 the side bearing is held in a horizontal position, as shown clearly in dotted lines in Fig. IV; but when the rod 2 is moved back to engage the clutch 7 with the other end of the drum the side bearing, D, is held in a vertical 80 position, so that the weight of the car and its contents will be supported on that side on the truck-beam, as shown clearly in Fig. VI.

The shaft 14 is provided at the end of the car with a toothed wheel or gear, 11, engaging with a worm or screw on the lower end of the vertical shaft 10, with a winch or hand-wheel on top, so that by turning the hand-wheel or the shaft 10 the shaft 14 beneath the car will be revolved. 85

A dog, 12, is pivoted to the lower side of the car and is attached to a rod, 15, extending along beneath the car, at the side, which rod is so connected with any desired number of latches, 16, that when the lower end of the dog 95 is moved inward and upward the inner end of the latch will be raised and its outer end depressed, to permit the side wall of the car, which is pivoted at a, to swing outward.

The car is pivoted at E to the truck at each 100 end, so as to tilt to either side, and the bunter-socket 17 is secured at each end of the car

to and between the sills I. This bunter-socket consists of a circular iron, 17, having an annular groove or channel around the outside, into which are fitted so as to move freely the projections 18 of the braces 21, which are bolted one to each sill, at each side the socket 17, and a projection on the iron 17 strikes against one of the projections 18 when the socket is turned in either direction, to limit the rotary movement of the bunter-socket to, say, an arc of about thirty degrees.

The rod 2, side bearing, D, and connections, and operating-lever 1, the shaft 14, and tripping-dog 12, with the latches 16, and operating-rod 15 are all duplicated, all these being arranged for each side of the car, so that the latter may be dumped either way or to either side.

To dump the car the operation is as follows: The lever 1 is moved into the position shown 20 in Fig. IV on the side on which it is desired to dump the car, raising the side bearing, D, into a horizontal position and moving the clutch 6 up into engagement with the drum 8, and the lever 1 on the opposite side is moved 25 just sufficiently to move the clutch away from the drum on that side, so that that drum will revolve freely and rapidly on the shaft. The hand-wheel on the shaft 10, on the side on which the car is to be dumped, is then turned, 30 revolving the drum and winding up the rope or chain, and thereby drawing down that side of the car, (the end of the chain or rope being made fast to the drum and extending down and around a pulley or roll in the truck-frame, 35 thence outward along the truck-frame and around another roll, and upward to the outer sill of the car, where it is made fast,) and tilting the car on its pivots at E. When this winding up of the chain or rope has proceeded 40 far enough to throw the center of gravity of the load outside the pivot E, the lower side of the car will then drop of its own weight, the chain unwinding rapidly from the opposite drum, and the dropping side striking with a 45 jar against the end F of the truck beam or frame, and the inside sill, C, also striking against a cushion or block, 22, on the truck-frame, just before the sill A strikes the end of the truck-beam at F, too great a jar or shock is 50 prevented. As the dropping side of the car passes down the end of the dog 12 strikes against a plate, 13, on the truck-frame, and the dog is thereby quickly thrown inward and upward, tripping the latches 16, (of which there may be 55 two or more along the side of the car,) and the outward pressure of the load or its own weight will swing the pivoted side of the car outward, and the whole contents of the car will be dumped upon the ground or into any receptacle 60 placed to receive it.

It will be perceived that after the dumping mechanism of the car is adjusted to a certain extent the weight of the car or its contents is utilized to complete the dumping operation, 65 which is accomplished with a jar, which will effectually and completely empty the car, and

this operation and its results differ very essentially from those in which the car is gradually and slowly pulled over, or tilted gradually through the whole movement, and the dumping is made much more effectual.

When the car is tilted back again, by winding up the opposite chains the side of the car swings in again by its own weight, and is locked by the latches 16 automatically by the weight of the dog 12 in swinging down.

If one car is dumped and the next one to which it is coupled remains stationary, the two bunter-sockets 17 will partially rotate between the projections 18, so that all strain on the coupling will be removed, and yet the socket cannot rotate sufficiently far to lose out the link-pin which secures the cars together.

It will be seen that as the side bearing, D, is pivoted at its upper end to the bottom of the car, when its lower end rests upon the truck-frame there will be sufficient movement of the bearing on its pivot as the car is being moved upon the road to allow of the differences of relative position between the car and its trucks in rounding curves, and yet the load will be fully supported by the bearings. As the chains are kept wound up on the drums, and the side bearings are provided with this forward and back play, there is little or no friction of the bearings on the truck-frame, and the car is effectually prevented from being accidentally dumped during transportation.

Having thus described my invention, what I claim as new is—

1. In a dump-car, the combination, with each side bearing pivoted at its upper end to the car, of the longitudinally-moving rod 2, the pivoted rod-operating lever 1, and the arm 4, connected at one end with said rod and at the other end with the side bearing, whereby the latter is moved into and out of supporting connection between the car and the truck, substantially as described.

2. In a dump-car, the combination, with a winding-drum arranged to revolve upon a shaft, of a sliding clutch to engage with either end of said drum, the longitudinally-moving rod provided with projections connected with said clutches to move the latter into and out of engagement with said winding-drum, and the pivoted lever connected to and operating said rod, substantially as described.

3. In a dump-car, the combination of a winding-drum arranged to revolve on a shaft, of sliding clutches to engage with said drum, of a longitudinally-moving rod provided with projections connected with said clutches to move the latter into and out of engagement with said drum, of a movable side bearing arranged between the car and the truck-frame to partially support the load, an arm connected at one end with the longitudinally-moving rod and at the other end with the side bearing, and an operating pivoted lever, whereby the side bearing is moved into and out of support.

ing connection between the car and the truck-frame, and the clutches are also moved into and out of engagement with the winding-drum, all by one movement of said operating-
5 lever, substantially as described.

4. In a dump-car, the combination, with the truck-frame, of the tilting car-frame, one or more latches for holding the side of the car in place, a latch-operating rod extending length-
10 wise the car and connected with the said

latches, and a weighted swinging dog connected with said latch-operating rod, whereby the side of the car is automatically released by the tilting of the car, and is also automatically locked again by the righting of the car, sub- 15
stantially as set forth.

WILLIAM H. PAIGE.
